RADIAL PUMP

William H. Mashinter, Chicago, Ill.

Application December 8, 1948, Serial No. 64,075

11 Claims. (Cl. 103—37)

1

This invention pertains to pump mechanism, injector mechanism or atomizing mechanism adapted to either supply solid liquid or spray comminuted fluid, or mixtures or fluid and solid.

Fuel injectors are substantially universally employed with low-speed oil engines of the diesel or semi-diesel type as a means for introducing thereto the heavier grade of liquid fuels such as are commonly used in engines of that type. But the lighter fuels employed, the higher operating speeds, and the wider range of speeds and loads required of gasoline engines present fuel injection problems that heretofore have never been satisfactorily solved.

An object of the present invention is to provide a fuel injector particularly adapted for use with engines of the high-speed type, employing lighter grades of fuel such as gasoline.

Another object is to provide a fuel injector so organized as to produce a fully developed readily combustible fuel spray within the very minute interval of time available at high operating speeds.

Another object of the present invention is to provide a substantially leak-proof fuel injection pump.

Another object is to provide a fuel injection pump that is substantially immune to leakage producing wear.

Another object is to provide an improved bellows type of pump capable of withstanding high pressures over long periods of use.

Another object of the invention is to provide automatic enriching mechanism and automatic leaning mechanism for injectors.

Another object is to provide a pump having a pressure responsive discharge valve so arranged as to be mechanically operated in the event of failure in pump pressure.

Another object of the invention is to provide pump mechanism so constructed and arranged that it may be used to pump solid liquid.

Another object of the invention is to provide a pump for supplying fluid under pressure and in measured quantities to means for utilizing the supplied fluid, as where fuel is sprayed into the cylinder of an engine, or where other liquid, such as water, is sprayed into such cylinder for power or antidentalating reasons.

Another object is to provide injecting means for supplying fuel to an internal combustion engine which may be used with manifold or separate cylinder injection and wherein the fuel is introduced in properly atomized condition over the entire range of operation of the engine, i. e., regardless of the operating speed of the engine.

2

Another object of the invention is to provide an injector for supplying fuel to an internal combustion engine, wherein a balanced diaphragm is used as the fuel pumping means.

5 Another object is to provide injecting means wherein the amount of fluid supplied therefrom is controlled by the pressure of the fluid delivered to the injecting means.

Another object of the invention is to provide 10 a fuel injector adapted particularly for use with engines of a high speed type, whether operating on heavy, intermediate, or light grade fuels.

Another object of the invention is to provide 15 an injector so constructed and arranged that it is not dependent upon any particular shape of actuating cam, but various shapes of cams may be resorted to as desired, to obtain a suitable variation of injector output with variations in injector speed of operation (i. e., engine speed).

20 Another object of the invention is to provide an injector so constructed and arranged that under certain conditions of operation it does not need, nor is it dependent upon a separate pump for supplying fuel thereto.

25 Another object of the invention is to provide an injector so constructed that it will operate over a large range of supply pressures.

Another object of the invention is to provide 30 a fuel injector so constructed and arranged that a complete degree of load-speed control is had by virtue of three independent controls over the amount of fuel emitted per injection, that is, (1) mechanical throttle, (2) variable supply pressure and (3) speed or injection operation.

35 Another object of the invention is to provide an injector using a controlled balanced diaphragm form of pump means for injection operation.

Another object is to provide a fuel injector 40 capable of effecting a more accurate control of the quantity of fuel injected throughout the entire range of engine speeds and loads.

Another object is to provide in a fuel injector 45 improved means for maintaining the same free of air or other gases.

Another object of the invention is to provide 50 a fuel injector pump so constructed and arranged that it can be regulated to supply fuel to cylinders of an internal combustion engine in a normal manner, whereby said cylinders may be fired successively in their proper order, or the pump may be regulated whereby selected numbers of cylinders may be selectively supplied with fuel for firing so that in idling, or low power, the fire occurs less often with a consequent saving in wear on the engine parts and pump parts.

Another object of the invention is to provide a fuel injecting pump which can be so constructed and arranged as to be operative to supply fuel to a cylinder of an internal combustion engine, whereby said cylinder, or a selected number of cylinders, fire intermittently while the other cylinders are inoperative, or may be so constructed and arranged that the pump supplies fuel to successive cylinders for firing, but the firing occurs less often for each revolution.

Another object of the invention is to provide a fuel injection mechanism wherein different banks of cylinders are readily controlled, such as controlling the functioning or non-functioning of such banks by a throttle, and where the timing of the injection may be changed by the throttle.

Another object of the invention is to provide a fuel injection system wherein the extent of the output of individual cylinders in each bank may be readily controlled independently of the other bank and where the total output of one bank of cylinders may be varied from the output of the other.

Another object of the invention is to provide an injection system wherein the timing of the injection can be accomplished in a plurality of ways, that is, by the arc of contact of the controlling cam or by means which advances or retards the position of the shaft in a rotary direction.

Another object of the invention is to provide a fuel injection system for an internal combustion engine or the like wherein there is provided mixture ratio adjusting means which is controlled by temperature variations of the engine such as the temperature of the lubricating oil of the engine or the engine temperature.

Another object of the invention is to provide a fuel injection system utilizing a balanced diaphragm so shaped that stress concentrations are relieved.

Another object of the invention is to provide a fuel injection system for internal combustion engines or the like utilizing control cam means wherein wear on the cam cannot change the relative output from respective cylinders and wherein there is substantially no side thrust on the cam shaft.

Another object of the invention is to provide a pump such as a pump for pumping fluids which is not limited to any known field but is adapted for use in a wide range of fields, such as that of air conditioning, fuel injecting, handling of slurry, or the like, and wherein the same pumping unit is adapted to handle different types of fluids without multiplying the parts thereof.

Another object of the invention is to provide a pumping unit wherein one pumping element can be readily removed without affecting the others and wherein the pumping elements are replaceable without the necessity of recalibrating the entire unit.

Another object of the invention is to provide a pump construction wherein no calibration is necessary.

Another object of the invention is to provide a fuel injecting system for an internal combustion engine wherein banks of cylinders of the engine may be used to fire alternately so that the cylinder wear is distributed.

Another object of the invention is to provide a pumping device for an internal combustion engine or the like wherein the drive for the pumping element can be the same as the ignition drive

but the timing of the unit and that of the ignition can be adjusted independently, one with respect to the other.

With these and various other objects in view, the invention may consist of certain novel features of construction and operation as will be more fully described and particularly pointed out in the specification, drawings and claims appended hereto.

10 In the drawings which illustrate embodiments of the device and wherein like reference characters are used to designate like parts—

Figure 1 is a sectional elevation through one form of fuel pump embodying the invention;

15 Figure 2 is a fragmentary sectional plan view taken substantially in the plane as indicated by the line 2—2 of Figure 1;

Figure 3 is a fragmentary sectional plan view taken substantially in the plane as indicated by the line 3—3 of Figure 1;

20 Figure 4 is a diagram showing the injection of fuel into successive engine cylinders and the successive firing of said cylinders controlled by the position of the pump cam of the pump illustrated in Figure 1;

Figure 5 is a sectional elevation of a modified form of fuel pump embodying the invention; and

25 Figure 6 is a sectional plan view taken substantially in the plane as indicated by the line 6—6 of Figure 5.

30 Referring first of all, more particularly, to the pump illustrated in Figures 1 to 3 inclusive, the pump comprises a body portion 10, and as the pump illustrated is for supplying fuel to a six cylinder internal combustion engine, the pump body may conveniently be of hexagonal form.

The body 10 is provided with the bore 12 closed by the top and bottom end closures 14 and 16 forming a cam shaft recess. The body portion 10 is provided with the pedestal 18 to which the control lever 20 is pivoted as at 22. The control lever comprises the arm 24 connected to suitable operating means (not shown) and the opposite arm 26 of said lever is loosely pivoted as at 28 to the cam shaft 30, whereby oscillation of the lever 20 raises and lowers the cam shaft 30 in a controlled manner. The cam shaft passes through a bearing portion 32 in the upper end closure 14, and within the bore 12 the shaft is provided with the cam portion 34. In the embodiment shown, the cam shaft is adapted to make one revolution for each seven revolutions of the crank shaft of the engine to which the pump supplies fuel, the engine being two-stroke cycled, hereinafter called two cycle.

35 The cam is provided with seven stages, for the purpose to be later described, said stages being indicated at 36, 38, 40, 42, 44, 46 and 48. The top stage 36 is provided with seven lobes 50, 52, 54, 56, 58, 60 and 62 (Figure 2), and successive stages 38, 40, etc., are provided with one less lobe. For example, stage 38 is provided only with lobes 50, 52, 62, 60, 58 and 56; stage 40 as illustrated in Figure 3 is provided with lobes 50, 52, 54, 62, 58 and 56; stage 42 is provided with lobes 50, 52, 60, 58 and 56; stage 44 is provided with lobes 50, 52, 60 and 56; stage 46 is provided with lobes 50, 52 and 56, and stage 48 is provided with lobes 50 and 52.

40 Cam portion 34 abuts against a spring seat 64 for one end of the spring 66, the lower end of said spring seating on spring seat 68 of the lower end enclosure. A portion of the cam shaft 30 extends through the bearing portion 32 of the closure 16 and is provided with a helical or spiral spline 72,

which engages with complementary spline means provided on the drive shaft coupling 74, said coupling being rotated by a suitable drive shaft, not shown, driven by the engine, such as the ignition or timing shaft.

The housing 10 is suitably supported as at 76 with respect to the engine through a support 78. Adjustable means 80 is provided for initially adjusting the timing of the cam shaft, and said means may conveniently take the form of a lug 82 provided with a suitable slot through which the housing 10 may be fixed by means of the bolt 84. This, then, relatively positions the splines, one with respect to the other.

The body is provided with equally spaced hydraulic pump housings 86, which, in the embodiment shown, are six in number. As each of the housings and their connections are similar, it will only be necessary to describe one of such housings.

The housings 86 are preferably co-planar, being located about mid-way of the depth of the bore 12, and each housing 86 is secured as by threads 88 to the housing 10 and is provided with the enlarged bore 90. A plunger or follower 92 extends through passage 94 provided in the housing 10 and is provided at its inner end 96 with a spring seat 98 for the spring 100, the opposite end of the spring seating on seat 102 of said bore. The outer or opposite end 104 of said plunger is the cam engaging end, and in the embodiment shown is of the mushroom type, though it may be understood, of course, that any type may be used.

Housing 86, provided with a bleed vent plug 106 to bore 90, is provided with the smaller bore 108 which communicates at one end with bore 90 and at the other end with the diaphragm recess 110. A suitable diaphragm 112 is secured in position by means of the collar 114 which in turn is secured by the pump housing end 116. It is, of course, understood that while the flat diaphragm 112 is illustrated, any other form of pulsating member may be used, such as a collapsible bellows or the like, such as illustrated in application Serial No. 541,969, which issued as Patent No. 2,559,364 on July 3, 1951. Diaphragm 112 is preferably made of a flexible, resilient material which is chemically inert to petroleum products or to the product being pumped and the hydraulic fluid, such as synthetic rubber, plastics as Teflon (tetrafluoro ethylene), methyl acrylate, or metals as 18-8 stainless steel or Hastelloy (a nickel, chromium, molybdenum, iron alloy) C and B, and the diaphragm may be such as shown and illustrated in an application filed of even date herewith Serial No. 64,076.

Check valve fitting 18 is secured as at 120 to the housing 86, the spring pressed valve 122 seating on seat 124, spring 126 urging said valve toward closed position, one end of the spring being seated on the valve and the other end of the spring being seated on perforated fitting 128. A tube such as an oil tube 130 is secured as at 132 to the fitting 118, and is connected to any suitable source of supply, preferably under slight pressure. The collar 114 and closure 116 form an outer fuel chamber 134 with the diaphragm 112, and closure 116 is connected to the fuel inlet check valve fitting 136 provided with the valve 138 seated toward the flow of fuel, that is, seated on seat 140, fuel supply line 142 being connected to said fitting 136 as at 144.

The valve is urged toward closed position by means of the spring 146 seated on perforated

fitting 148. Fuel supplied past the check valve 138 is supplied to chamber 134, by passages 150 and 152, and passage 150 communicates with the outlet check valve fitting 154 provided with the check valve 156 seated toward the passage 150, being urged toward closed position on seat 157 by means of the spring 158 seated on the perforated fitting 160. Fittings 128, 148 and 160 are adjustable whereby the tension of the respective springs which are seated thereon may be varied. The outlet supply line 162 is secured to the fitting 154 as at 164 and said line 162 is secured to a suitable nozzle for supplying fuel to a cylinder of an internal combustion engine, such as shown in application Serial No. 617,752, filed September 21, 1945 for Spray Nozzle, now Patent No. 2,555,803. Each of the separate hydraulic pumps are connected in a similar manner to their respective cylinders.

In operation of this form of the device, let it be assumed that the cam shaft 30 is depressed so that stage 36 engages the followers 92. In this stage the pumps will be successively operated, that is, each follower will be moved against its spring 100 by contact with the lobes 50, etc., causing displacement of liquid in the respective hydraulic pump housings 86, which in turn actuates the respective diaphragms 112 whereby reciprocation of the diaphragms causes a pumping action of the fuel supplied to the respective cylinders.

If it is desired to decrease the throttle, the cam shaft 30 is raised to the selected stage. For example, let it be assumed that the cam shaft is raised so that the followers contact course 48. In this case only one lobe is utilized. Inasmuch as there are seven lobes and six cylinders, the actuation will be as illustrated in Figure 4.

Let it be assumed that engine cylinder number 1 to be affected is indicated by station 166, successive engine cylinders numbers 2, 3, 4, 5 and 6 being shown at stations 168, 170, 172, 174 and 176. Let it be assumed that the fuel injection pumps for the respective cylinders are also at 166, 168, etc., number one cylinder will fire at 178 and the engine crank shaft will then rotate through 360°, plus 60° and cylinder number 2 will fire at 180. While the crank shaft was going through 420°, the cam shaft 30 rotated through 60°. The crank shaft then rotates through another 420° whereby cylinder number 3 fires at 182. Cylinder number 4 fires 420° later at 184. Cylinders numbers 5 and 6 fire 420° at 840°, at 186 and 188, respectively, and for each 420° of the crank shaft the cam shaft rotates through 60°. Thus the cylinder wear is distributed while idling (minimum throttle).

It is understood that if six lobes were used on the cam shaft instead of seven, the cam shaft in the lowest idling position would run at $\frac{1}{6}$ the speed of the crank shaft, that is at stage 48, only one and the same cylinder would fire each time instead of successive cylinders, such as where seven lobes are used. Each cam lobe and each cam stage is so shaped that as the cam shaft is being moved downwardly to cause successive cylinders to be brought into operation, the mixture to the operating cylinders is first enriched up to the time that the followers change stages, at which time the lobes in the newly entered stage cause the mixture to get leaner so that the effect of causing cylinders to become operative is a gradual one, from one stage to the other, thus causing a smooth power flow. The shape of the lobes in the embodiment illustrated is thus flared

or tapered upwardly on each side of the center of the lobe, such as shown at 180 (Figure 2).

Also, it will be noted that as the cam shaft 30 is raised or lowered the spline 72 causes a change of relative position between shaft 30 and the driving shaft of coupling 74, whereby the injection time is advanced or retarded, depending upon the shape of the spline and the stage engaged, and type of service to which the engine is put.

Referring now to the construction illustrated in Figure 5, the device comprises the housing 182 provided with the connection 184 secured in a suitable support 186, the position of the housing being adapted to be adjusted as by adjusting means 188, which may conveniently take the form of the base plate 190, having a suitable slot through which the bolt 192 extends.

The housing is provided with the bore 194 closed by the top closure 196, said closure being provided with the bearing 198 through which one end of the cam shaft 200 extends. A pedestal 202 is provided on the housing, and the lever 204 is pivoted thereto as at 206. The lever, as shown, is in the form of a bell crank provided with the arm 208 to which the operating means 210 is adjustably pivoted as at 212. The lever is provided with the arm 214 adapted to engage the outwardly projecting end of the cam shaft 200 for controlling the position of said shaft, the end of the shaft being shown as a button 216 resiliently mounted on spring 218 disposed in recess 220 of the cam shaft. The lower end of the shaft 200 extends through the bearing portion 222 of the housing and is provided with the tang 224 received in a suitable slot 226 in the drive shaft 228. A spring 230 is disposed to seat at one end on the spring seat 232 and at the other end on the antifriction bearing 234 for urging the cam shaft upwardly.

In the embodiment shown, the device is adapted to be operative to cause operation of certain selected cylinders and in this case the pumping elements are placed in two banks or courses. For example, the pumps for cylinders 1, 3 and 5 are in one course and the pumps for cylinders 2, 4 and 6 are in another course. The pumping elements in each course are similar.

Referring first of all to the upper course, a gasoline inlet manifold 236 is supplied from a suitable source, not shown, and is secured as at 238 to the housing 182. Said manifold communicates through passage 240 with the inlet valve 242 seated toward the manifold, being spring pressed as at 244 and provided with the spring adjusting and retaining means 246 apertured to permit passage of fuel therethrough. The valve communicates through passage 248 with the fuel diaphragm chamber 250, which in turn communicates through passage 252 with the outlet valve 254, the valve being adapted to be secured to suitable piping (not shown) for supplying the proper cylinder, as for example cylinder number 1.

A check valve 256 is provided seating against the flow, being urged toward closed position by the spring 258 which in turn is retained by the apertured retaining and adjusting member 260. The diaphragm 262 is cupped shape, sealed and bonded to the ring 264 formed on the member 266. The inside of the diaphragm communicates through passage 268 with the bleed plug 270. The inside of the diaphragm also communicates through passage 272 with the passage 274 which

in turn communicates with passage 276, a check valve 278 seating toward passage 276 whereby oil contained in the bore 194 may be supplied past the check valve 278 which closes toward the bore 194 to the inside of the diaphragm 262. The valve 278 is spring pressed by spring 280, the spring being seated on the apertured retainer and adjusting members 282.

A plunger 284 is mounted in passage 286, which is aligned with passage 272, and said plunger is provided with the roller follower 288 pivoted to the housing 290 provided on the plunger 284, the spring 292 urging the follower toward the cam lobe 294. The cam lobe 294 is bevelled and shaped as illustrated in Figure 6 whereby the roller 288 always contacts the cam 294 over a line contact.

Cam lobe 296 is similar to cam lobe 294, and assuming that the pump illustrated for the lower course is shown for cylinder number 4, the lobe is spaced 180° from lobe 294.

Manifold 236 is secured as at 300 to the housing and communicates with spring pressed check valve 302 similar to check valve 242 closing toward manifold 236. The check valve communicates with fuel chamber 304 formed by threaded plug 306 retained by cap 308. The chamber 304 communicates with passage 310 which communicates through check valve 312, similar to check valve 254, and suitable piping (not shown) with cylinder number 4, check valve 312 seating toward the chamber 304. The diaphragm 314, similar to diaphragm 262, is bonded to collar 316 which is part of member 318, and the inside of the diaphragm communicates through passage 320 with the check valve 322 which in turn communicates with the bore 194, check valve 322 being provided with the ball 324 which seats toward the bore 194, being spring pressed by spring 326, the spring being retained by the apertured adjusting and retainer member 328. The inside of the diaphragm also communicates through passages 330 and 332 with bleed vent plug 334. The plunger 336 is spring pressed by spring 338 and reciprocates in passage 340, aligned with passage 320, the spring urging the housing member 342 toward the cam 296, the housing being provided with the bevelled follower roller 344.

Below the cam 296 there is provided a cam lobe 346 which is operative when cam lobes 294 and 296 are in inoperative raised position whereby only the lower banks of cylinders are supplied with fuel. Operation of the lever 204 causes vertical movement of the cam shaft 200 to dispose the cam surfaces 294 and 296 in operative relation with the followers, as illustrated in Figure 5, or the cam shaft may be moved to a position where follower 288 is inoperative, as where it contacts the cylindrical portion 348 of shaft 200, and follower 332 is operative by the cam 346.

When the follower 344 is operative by the cam 346, and it is desired to cause operativeness of the other bank of cylinders, the lower banks of cylinders are first enriched by cam 346 due to the shape of said cam, and as the cam shaft 200 is depressed the roller follower 344 will travel down the slope 350 so that when the upper bank of cylinders become effective with the lower banks of cylinders, that is, when the rollers 344 and 288 engage cams 296 and 294, respectively, the six cylinders will be lean so that a gradual flow of powder will result. Operation of the followers, of course, causes oscillation of the diaphragms, causing a pumping action from the manifold 236 to the outlet fittings and thus to

the cylinders, the diaphragms being actuated by the oscillation of the plungers 284 and 336, causing the motion of said plunger to be transmitted through the oil to the diaphragms. Thus operation is effected with a balanced diaphragm condition.

It is to be understood that this application is not to be limited by the exact embodiments of the device shown, which are merely by way of illustration and not limitation as various and other forms of the device will, of course, be apparent to those skilled in the art without departing from the spirit of the invention or the scope of the claims.

I. claim:

1. In a pump, the combination of a housing having a lubricant containing cam shaft recess therein, a cam shaft disposed in said recess and having an end projecting from each end of said housing, means connected to one end of said shaft for bodily moving said shaft, means operatively connected to the other end of said shaft for rotating said shaft, a plurality of courses of cams on said shaft within said recess, said cams comprising cam lobes, the number of cam lobes in each course being different from the number of lobes in the other courses, and a plurality of pumping elements disposed in said housing radially of the axis of said shaft, each of said pumping elements having a plunger adapted to be selectively reciprocated by the cams of the respective courses.

2. In a pump, the combination of a cam shaft, means for rotating said shaft, a plurality of courses of cams on said shaft, a plurality of pumping elements, means for operating said pumping elements including a reciprocable cam follower for each of said elements, and means for effecting an engagement of said followers and a selected course of cams, whereby the cams in the other courses are inoperative to actuate said pumping elements.

3. In a pump, the combination of a cam shaft, means for rotating said shaft, a plurality of courses of cams on said shaft having faces inclined longitudinally with respect to the axis of rotation of said shaft, a plurality of pumping elements, means for operating said pumping elements including a reciprocable cam follower for each of said elements, and means for effecting an engagement of said followers and a selected course of cams, whereby the cams in the other courses are inoperative to actuate said pumping elements.

4. In a pump, the combination of a cam shaft, means for rotating said shaft, a plurality of courses of cams on said shaft, a plurality of pumping elements, means for operating said pumping elements including a reciprocable cam follower for each of said pumping elements, and means for effecting an engagement of said followers and selected courses of cams, whereby the cams in the other courses are inoperative to actuate said pumping elements.

5. In a pump, the combination of a cam shaft, means for rotating said shaft, a plurality of courses of cams on said shaft, said cams comprising cam lobes, the number of cam lobes in each course being different from the number of lobes in the other courses, a plurality of pumping elements disposed radially of the axis of said shaft, means for operating said pumping elements including a reciprocable follower for each of said elements, and means for bodily moving

5 said shaft to selectively engage said followers with a course of said cams.

6. In a pump, the combination of a cam shaft, means for rotating said shaft, a plurality of courses of cams on said shaft, said cams comprising cam lobes, the number of cam lobes in each course being different from the number of lobes in the other courses, said lobes having faces inclined longitudinally with respect to the axis 10 of said shaft, a plurality of pumping elements disposed radially of the axis of said shaft, means for operating said pumping elements including a reciprocable cam follower for each of said pumping elements, said followers being adapted for movement in a plane at right angles to the axis of said shaft, and means for moving said shaft axially to selectively engage said followers with a course of said cams.

7. In a pump, the combination of a cam shaft, 20 rotating means for said shaft, a plurality of courses of cams on said shaft, a plurality of pumping elements, means for operating said pumping elements including reciprocable cam followers disposed radially of the axis of said shaft, and means for moving said shaft axially for effecting an engagement of said followers and a selected course of cams, whereby the cams in the other courses are inoperative to actuate 25 said pumping elements and to alter the relative position of said shaft with respect to said rotating means.

8. In a pump, the combination of a cam shaft, means for rotating said shaft, a plurality of courses of cams on said shaft, a plurality of courses of pumping elements disposed radially of the axis of said shaft, means for operating said pumping elements including a reciprocable cam follower for each of said pumping elements, and means for selectively engaging one or more 30 courses of cams with one or more courses of followers.

9. In a pump, the combination of a housing having a lubricant containing cam shaft recess therein, a cam shaft disposed in said recess and having an end projecting from each end of said housing, means connected to one end of said shaft for axially moving said shaft, means operatively connected to the other end of said shaft for rotating said shaft, a plurality of courses of cams on said shaft within said housing, a plurality of pumping elements disposed in said housing radially of the axis of said shaft in a plurality of planes, and means for operating said pumping elements including a reciprocable cam follower for each of said pumping elements adapted to be selectively engaged and disengaged by the courses of cams.

10. In a pump, the combination of a cam shaft, means for rotating said shaft, a plurality of courses of cams on said shaft having faces inclined longitudinally with respect to the axis of rotation of said shaft, a plurality of pumping elements, means for operating said pumping elements including a reciprocable cam follower for each of said pumping elements adapted for movement in a plane at right angles to the axis of said shaft, and means for effecting an engagement of said followers and a selected course of cams, whereby the cams in the other courses are inoperative to actuate said pumping units.

11. In a pump, the combination of a cam shaft, means adjustably connected to said shaft for rotating the same, a plurality of courses of cams on said shaft, a plurality of pumping elements, means for operating said pumping elements in-

cluding a reciprocable cam follower for each of said pumping elements, and means for bodily moving said shaft for effecting an engagement of said followers and a selected course of cams whereby the cams on the other courses are inoperative to actuate said pumping elements and to alter the relative position of said shaft with respect to said rotating means.
